United States Patent Office.

JOSEPH E. DUST, OF HYATTSVILLE, OHIO.

Letters Patent No. 60,841, dated January 1, 1867.

IMPROVED TABLE.

The Schedule referred to in these Letters Patent and making part of the same.

TO ALL WHOM IT MAY CONCERN:

Be it known that I, JOSEPH E. DUST, of Hyattsville, Miami county, Ohio, have invented a new and useful Dining Table; and I do hereby declare the following to be a full, clear, and exact description thereof, reference being had to the accompanying drawings, making part of this specification. My invention relates to an arrangement of folding table with revolving waiter.

Figure 1 represents, in the folded form, a table embodying my invention.

Figure 2 is an under side view of the same in its extended form.

The top, A B, is preferably of circular form, and consists of one stationary leaf A, permanently attached to the stationary legs C C', and one folding leaf B, which is hinged, b, to the leaf A. D D' are the movable legs hinged by folding-boards E E' E'' E''' to the stationary legs C C', and grooved, d d', on their upper edges to slide along dove-tailed tongues F F' on the under side of the leaves A B. G is a rotary leaf or waiter of circular form, having a boss, H, and centre pin, shown by dotted lines I, resting upon and occupying sockets J attached to the folding leaf B. In the folded condition, as represented in fig. 1, the table forms a convenient sideboard.

I claim herein as new, and of my own invention—

The folding table A B, stationary legs C C', sliding legs D D', and rotary waiter G, forming a convertible, self-waiting, and folding table and sideboard.

In testimony of which invention I hereunto set my hand.

J. E. DUST.
